UNITED STATES PATENT OFFICE.

JOHN WICKS, OF COLUMBUS, OHIO, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

1,314,455.

Specification of Letters Patent. Patented Aug. 26, 1919.

Application filed February 23, 1916. Serial No. 80,042.

To all whom it may concern:

Be it known that I, JOHN WICKS, a citizen of the United States of America, and a resident of Columbus, county of Franklin, 5 and State of Ohio, have invented certain new and useful Improvements in Automatic Telephone Systems, of which the following is a specification.

My invention relates to automatic telephone systems and has particular reference to methods of handling toll or long distance connections in such systems. In general my invention contemplates the provision of a comprehensive system of automatic calling 10 over serially related long distance lines, the arrangement being such that an operator at any exchange in the system is enabled to establish connection with subscribers in any other exchange without the intervention of 15 intermediate operators.

I am aware that automatic calling over toll lines is not altogether new but to the best of my present knowledge such calling has heretofore been restricted to lines 20 extending between two exchanges only. The system of my invention makes a substantial advance over what is old in the art by providing means whereby an operator at an originating exchange can connect through 25 the medium of automatic switches with subscribers in a second exchange; and can also connect, by means of one of the same switches, with a toll line extending to a third exchange, where the connection may 30 again be extended to local subscribers or to other toll lines.

Since at the intermediate exchanges all the toll lines must be capable of being called as well as of calling, and since they 35 must be arranged for local as well as through connections, in which latter case the impulses and signaling currents have to be relayed, special apparatus must be provided to take care of these different contingencies; 40 and it is the particular object of my invention to provide for each toll line terminating at an intermediate exchange such an apparatus, as will appear more clearly hereafter.

50 A further object of my invention is to provide means included in the above apparatus whereby a distant operator, having operated the intermediate exchange apparatus to select a line to a third exchange, may at 55 her option signal the operator at the third

exchange manually, or connect automatically with local subscribers at the third exchange.

Further objects of my invention are to incorporate the foregoing into a system in which the lines are phantomed in accordance 60 with well known practice; to provide means for sending regulated operating impulses over simplex circuits superimposed on the physical lines in the above system; and to accomplish all the foregoing without detracting from the talking efficiency of the 65 lines, or interfering with their use for regular manually established connections.

These and other objects will appear more clearly and will be explained more fully in 70 the detailed specification, reference being had to the accompanying drawings.

For a clear understanding of the drawings, Figures 2, 3, 4, 5, 6, 7, and 8 should be arranged in order with their lines at the 75 sides thereof in alinement, Fig. 1 should be joined at its right hand end to the left side of Fig. 2, Fig. 9 should be joined at its left hand end to the right side of Fig. 8, Fig. 5^a should be joined at the top to the bottom of 80 Fig. 5, and Fig. 10 should be joined at its left hand end to the right side of Fig. 5^a. The apparatus shown in Figs. 1, 2, and 3 is located in what I shall hereinafter designate as the No. 1 exchange, the apparatus 85 shown in Figs. 4, 5, 6, 5^a, and 10 is located in what I shall hereinafter designate as the No. 2 exchange, while the apparatus shown in Figs. 7, 8, and 9 is located in what I shall hereinafter designate as the No. 3 exchange. 90

When the drawings are properly laid out and joined together it will be seen that I have shown two toll lines, indicated by reference characters 105—106 and 205—206, extending from the No. 1 exchange to the No. 95 2 exchange, and two other toll lines, indicated by reference characters 305—306 and 405—406, extending from the No. 2 exchange to the No. 3 exchange. Each toll line is shown connected through a repeating coil 100 with a repeater and a jack at each end. For example, the toll line 105—106 is shown connected by means of repeating coil R^a at the No. 1 exchange with the jack J^a and the repeater E^a, and by means of repeating coil 105 R^b at the No. 2 exchange with the jack J^b and the repeater M^b. It will be readily seen that each of the other three toll lines is similarly equipped. In addition to the above, each toll line has an extension by 110

way of its associated repeater at the intermediate exchange extending to a toll selector N^1 , N^2 , etc., and also a second extension leading to multiple contacts in the banks of these toll selectors. It is plain that the toll selectors provide means for establishing through connections over two serially related toll lines.

Apparatus is also provided in connection with the two parallel toll lines 105—106 and 205—206 whereby a phantom circuit is formed extending from jack J^3 in the No. 1 exchange to jack J^4 in the No. 2 exchange. Similarly, a second phantom circuit is superimposed on parallel toll lines 305—306 and 405—406 and extends from jack J^9 in the No. 2 exchange to jack J^{10} in the No. 3 exchange. It is to be understood that the phantom circuits are adapted for use in manually established connections only while the physical circuits may be used both for manually and automatically established connections.

To better facilitate the understanding of my invention I have elected to show a part of the apparatus in operated position whereby a complete circuit connection has been established between a calling substation A (Fig. 1) in the No. 1 exchange, and a called substation A² (Fig. 9) in the No. 3 exchange. The said connection extends from substation A by way of line conductors 11 and 12, conductors 13 and 14, multiple jack J^{13} , cord circuit P' , jack J^5 , repeating coil R^8 , toll line 105—106, repeating coil R^4 , repeater M^2 , toll selector N^4 , repeater M^3 , repeating coil R^7 , toll line 305—306, repeating coil R^8 , repeater E^3 , and connector H^2 to the line conductors of substation A².

The substation A (Fig. 1) may be of any suitable type or construction and as shown herein is of the general type disclosed in British patent to T. G. Martin, No. 1419 of 1910. It comprises essentially the receiver 2, transmitter 3, switch hook 4, ringer 5, and condenser 6. Being an automatic substation it is also provided with a pair of impulse springs 7 and 8 controlled by the impulse wheel 9 through the medium of a finger hole dial (not shown).

The line conductors 11 and 12 of the substation A are connected at the No. 1 exchange to the individual line switch C which may be of the general type disclosed in British patent to R. W. James, No. 26,301 of 1906; being, however, of the particular type shown in United States Letters Patent No. 1,078,690, granted Jan. 17th, 1912, to Frank Newforth. Since line switches of the above type are well known and since they form no part of my invention an extended description will not be given. It will suffice to say here that through the medium of line switch C the line of substation A is given access to a plurality of selector switches

(not shown) which may be of the general type disclosed in the British patent to Automatic Telephone Manufacturing Co., No. 2543 of 1914. A three conductor trunk line which may be extended to one of these selector switches is indicated by reference characters 34, 35, and 36.

For the purpose of controlling a group of line switches such as the line switch C, there is provided a master switch D, which is of the general type disclosed in British patent to R. W. James, No. 26,301 of 1906; being, however, more nearly of the particular type disclosed in British patent to T. G. Martin No. 1419 of 1910. The function of the master switch, as is well known, is to maintain all the idle line switches of its associated group in operative relation with an idle trunk line.

In addition to the line switch C there is also provided for the line of substation A a multiple jack J^{13} , which, as shown herein, is directly accessible to the toll operator. It is to be understood that the toll operator may complete connections locally by any other known method, however, the method shown having been chosen principally on account of its simplicity.

At P' I have shown a toll operator's cord circuit which may be of any suitable type. As shown herein, it comprises among other details the battery supply relay 51 which, in connection with sleeve relay 50, controls the supervisory lamp L'; and the ring up locking relay 52 which, in connection with the sleeve relay 55, controls the supervisory lamp L². Keys K¹⁰ and K¹² are ringing keys and key K¹¹ is a listening key. The talking strands of the cord are connected through condensers 56 and 57.

The toll operator, besides having access to lines of the local subscribers, has before her multiple jacks which are terminals of toll lines extending to other exchanges. I have shown three such jacks, J' , J^5 , and J^6 , which are terminals of circuits extending to exchange No. 2. Of these three circuits, the physicals, represented by jacks J' and J^6 , are equipped for automatic calling, as will presently be made clear.

The apparatus shown at F² (Fig. 3) is, with the exception of the calling device S⁸, individual to the toll line 105—106. The calling device S⁸ may be common to a number of toll lines, or, preferably, there may be one such calling device for each toll operator. The key K³ serves to associate the corresponding toll line with the calling device at the proper time. The reference character 76 represents an impulsive relay of high resistance and having magnetically distinct cores. Reference characters 510, 74, 77, and 75 indicate, respectively, an impedance coil, a cut-off relay, a switching relay, and an ordinary drop for receiving signals.

The cut-off relay 74, when actuated, serves to disconnect the connections extending to the repeater E^2 and to the drop 75. The switching relay, when actuated, shifts the 5 normal ground connection of the impulsing relay 76 to the ungrounded pole of battery B. A slight inspection of the drawings now will show that each toll line is equipped at its terminus in the No. 1 exchange or No. 3 10 exchange with apparatus similar to that shown at F^2 . Or, in other words, the apparatus shown at F' (Fig. 3), F^3 (Fig. 7), and F^4 (Fig. 7) is precisely like that shown at F^2 (Fig. 3) which has just been described.

15 At the No. 2 exchange the toll line 105—106 is extended through the medium of repeating coil R^4 to the multiple jack J^6 . The apparatus directly associated with jack J^6 , indicated by reference character O^2 , comprises 20 a cut-off relay 125, a drop 126, and a key K^4 by means of which the corresponding toll line may be associated with the calling device S^4 . The apparatus shown at O' , O^3 , and O^4 is precisely like that shown at O^2 .

25 The repeater M^2 , which has been previously referred to, is of utility for setting up automatic connections in either direction over its associated toll line. For handling incoming automatic calls from the No. 1 30 exchange a four conductor trunk line indicated by reference characters 201, 202, 203, and 204 is provided. This trunk line may be traced through Fig. 5 to Fig. 5^a where it terminates in the toll selector N^4 . Similarly, 35 the repeater M' , associated with toll line 205—206 and precisely like repeater M^2 , is provided with a trunk line indicated by reference character 220, which extends through Fig. 5 to Fig. 5^a where it terminates in the 40 toll selector N^4 . The repeaters M^3 and M^4 , associated, respectively, with toll lines 305—306 and 405—406, are also precisely like repeater M^2 in construction and function; and are also provided each with a trunk line, 45 which trunk lines are indicated, respectively by reference characters 221 and 207, and which extend through Fig. 5 to Fig. 5^a and there terminate, respectively, in toll selectors N^2 and N' . More briefly stated, each toll 50 line terminating in the No. 2 or intermediate exchange has access, through its associated repeater M' or M^2 , etc., to a toll selector such as N^2 or N^4 , etc. The operation and functions of the various relays of the M type 55 of repeaters will be described fully in the detailed specification. It may be mentioned here, however, that the impulsing relay 112 of repeater M^2 and corresponding relays of the repeaters M' , M^3 , and M^4 are similar to 60 relay 76 (Fig. 3) which has already been described.

The toll selector N^4 is of the general type of selector switch disclosed in U. S. Letters Patent No. 815,321, granted March 31, 1906, 65 to Keith, Erickson and Erickson; being,

however, more nearly of the particular type disclosed in British patent to the Automatic Telephone Manufacturing Co., No. 2543 of 1914. Among other details, the toll selector N^4 comprises a bank of contacts arranged 70 in horizontal rows or levels, which contacts are adapted to be engaged by a set of wipers 270, 271, 272, and 273, carried upon a shaft (not shown) which has a vertical movement controlled by the vertical magnet 256, and a 75 rotary movement controlled by the rotary magnet 257. The operation of the various parts of the switch is controlled through the medium of the double wound line relay 250. Means for permitting the switch to be 80 restored to normal position is provided in the release magnet 254 which, upon energizing, withdraws the retaining pawls from the shaft. The contacts 262 and 263 make against their respective springs only when 85 the shaft has been raised one or more steps from its normal position. The relay 260, bridged across the line conductors 265 and 266, is of high resistance and is designed to operate on alternating current. The relays 90 255, 258, and ringing relay 261 are slow acting, *i. e.*, each of these relays is able to retain its armature for an instant after its energizing circuit has been broken.

Considering now the bank contacts of the 95 toll selector N^4 more in detail, it will be seen that I have shown in the drawing (Fig. 5^a) three of the horizontal levels and two sets of contacts in each level. It is to be understood, however, that there may be more contacts than shown herein, there being generally provided in actual practice ten of the horizontal levels each with ten sets of contacts. From the first set of contacts of the first level there extends a three conductor 100 trunk line, indicated by characters 212, 213, and 214, which terminates in the connector switch H^3 (Fig. 10). The second set of contacts in the first level is provided likewise with a trunk line 215, which extends 105 to a connector switch (not shown) similar to the connector H^3 . In the same manner each of the other sets of contacts in the first level may be provided with a trunk line extending to a connector switch similar to connector H^3 . 110

The first set of contacts in the second level is provided with a trunk line whose conductors are separately numbered 208, 209, 210, and 211, and which extends upward through Fig. 120 5 and terminates in the repeater M^3 (Fig. 6). The second set of contacts in the second level is provided with a trunk line, indicated by reference character 216, which extends upward through the lower right hand corner of 125 Fig. 5 and terminates in the repeater M^4 (Fig. 6). Since the repeaters M^3 and M^4 are associated, respectively, with the toll lines 305—306 and 405—406, which extend to the No. 3 exchange, it will be clear that 130

the second level is the level assigned to the toll lines extending between the No. 2 and No. 3 exchanges. In fact were there other such toll lines besides the ones shown they 5 would appear at additional contacts in the second level.

In like manner the first and second sets of contacts in the third level are terminals of trunk lines indicated by reference characters 10 217 and 218, and which terminate, respectively, in the repeaters M^2 and M' (Fig. 4). Whence it follows that the third level is the level assigned to the toll lines extending between the No. 2 and No. 1 exchanges. Were 15 there additional exchanges and connecting toll lines terminating in the No. 2 exchange, the toll lines extending to each separate additional exchange would be assigned to a separate level in the toll selector bank such 20 as the fourth or fifth level, for example. Further consideration of Fig. 5^a will show that each trunk line leading from the contacts in the bank of selector N^4 is also multiplied to corresponding contacts in the 25 banks of all the remaining toll selectors. From the foregoing considerations the following conclusion may be drawn: The toll lines terminating in the No. 2 or intermediate exchange are provided each with a toll 30 selector switch, which switches have access in common to connectors for completing local connections, and also have access to all of the toll lines themselves, the connectors and various groups of toll lines being as 35 signed to separate levels in the toll selector banks.

Continuing with the description of the apparatus, it has already been mentioned that the repeater M^3 and apparatus F^3 are 40 similar to corresponding parts in Figs. 4 and 3. At E^3 (Fig. 8) I have shown a repeater which is of the general type disclosed in U. S. Letters Patent No. 1,136,912, granted April 20, 1915, to Talbot G. Martin, although 45 the circuits are modified somewhat to enable the repeater to operate in conjunction with the apparatus shown at F^3 (Fig. 7). The operation and functions of the various 50 relays of the repeater will be described more fully in the detailed specification.

By means of conductors 510 and 511 the repeater E^3 is connected directly with connector H^2 (Fig. 9), which is of the general type of connector disclosed in U. S. Letters 55 Patent No. 815,176, granted March 13, 1906, to Keith, Erickson and Erickson; being however, more nearly of the particular type disclosed in the British patent to the Automatic Telephone Mfg. Co., No. 2270 of 1914. 60 Among other details, the connector H^2 comprises a bank of contacts arranged in horizontal rows or levels, which contacts are adapted to be engaged by a set of wipers 530, 531, and 532 carried upon a shaft (not 65 shown) which has a vertical movement con-

trolled by the vertical magnet 518, and a rotary movement controlled by the rotary magnet 519. The usual side switch comprising the wipers 525, 526, 527, and 528 is controlled by the private magnet in the well known manner. The operation of the various parts of the switch is controlled by the double wound line relay 512 which relay, in the case of purely local connections, also serves to supply talking current to the calling line. The called line is provided with talking current from the windings of the double wound answering bridge relay 515. The ringing relay 524 affords means for projecting ringing current over the called line to signal the called subscriber. Means for restoring the switch to normal position is provided in the release magnet 516 which, upon energizing, withdraws the retaining pawls from the shaft and restores the side switch wipers to their first position. The contacts 536 and 537 make contact with their respective springs only when the shaft has been raised one or more steps from its normal position. The relays 517 and 521 are slow acting.

The connector H^2 has access through its wipers and bank contacts to a group of subscribers' stations one of which is shown at A^2 . The substation A^2 may be similar to substation A (Fig. 1) already described, and is like that substation provided with an individual line switch, shown at C^2 , and with multiple jacks, of which one is shown at J^{14} . Each of the substations in the No. 3 exchange is of course, similarly provided with a line switch and with multiple jacks, the former being of service in setting up local connections, while the latter enable the toll operator or operators to connect the corresponding substations with toll lines extending to other exchanges, as for example, the toll lines 305—306 and 405—406. For this purpose cord circuits are provided, one of which is shown at P^2 (Fig. 8) this cord circuit being similar to the one shown at P' (Fig. 2).

The repeaters E' and E^2 (Fig. 2) and E^4 (Fig. 8) are similar to repeater E^3 (Fig. 8) and are each assumed to be connected directly to a connector switch such as connector H^2 (Fig. 9); one of these connectors, the one to which repeater E' is connected, being in fact, shown at H' (Fig. 1). The connectors to which repeaters E^2 (Fig. 2) and E^4 (Fig. 8) are connected are not shown. The connector H' and associated connectors are provided for the purpose of completing connections to the lines of substations terminating in the No. 1 exchange, one of which, the one shown at A (Fig. 1), has already been described.

It has been explained how the toll selectors have access through one of their bank levels to connector switches such as the con-

5 nector H^3 (Fig. 10). The connector H^3 and associated connectors are similar to connector H^2 (Fig. 9) and are provided for the purpose of completing connection with the lines of substations terminating in the No. 2 exchange, one of which substations is shown at A' (Fig. 10). The substation A' is similar to substation A (Fig. 1) and like that substation is provided with an individual 10 line switch C' for use in establishing local automatic connections; and is also provided with multiple jacks, one of which is shown at J^{15} . These latter are provided to enable the toll operator or operators to complete 15 connections between a calling (or called) subscriber, the one at substation A' , in this case, and a toll line. For this purpose there are provided cord circuits which may be similar to the one shown at P' . The cord 20 circuit shown at P^3 is somewhat different from the other cord circuits shown in that it is provided with a ring up and locking supervisory relay in each end of the cord instead of only in the toll end. This cord 25 circuit may be used for manually completing through toll connections.

While I have shown the toll selectors and repeaters E' , E^2 , etc., as having direct access to the connector switches, it will be evident 30 to those versed in the art that selector switches may be used in the well known manner for increasing the capacity of the system. Selectors which may be used are of the type disclosed in British patent to 35 the Automatic Telephone Manufacturing Co., No. 2543 of 1914.

The various devices for preventing interference between the two physical circuits and between the physical and phantom circuits form no part of this invention, since 40 they are fully described and claimed in the co-pending application of Frank Newforth, Serial No. 69633, filed Dec. 31, 1915.

It is thought best however, to describe 45 these devices briefly as follows: Considering the phantom circuit superimposed on toll lines 105—106 and 205—206, the phantom repeating coil R^5 has its line windings joined by a pair of condensers 501 and 502 50 in series, and in the same manner the repeating coil R^6 has its line windings joined by the condensers 503—504. These condensers prevent the flow of direct current between the physical circuits. The junction 55 of each of these condenser pairs is connected to the junction of a pair of low resistance high impedance retardation coils, indicated by reference characters 505—508, inclusive, which are themselves connected in series 60 with the exchange battery. These coils serve to take up the charging and discharging currents of the condenser pairs, thereby preventing these currents from interfering with the operation of the impulsing relays 65 such as relay 76 (Fig. 3.) To admit of using

alternating current on the phantom circuit for signaling without interfering with the operation of the impulsing relays, such as relay 76 (Fig. 3), the retardation coils 510 and 512 (Fig. 3) and 511 and 513 (Fig. 4) 70 are provided. Each of the calling devices S' , S^2 , etc., is provided with a condenser 514, 515, etc., in shunt thereof, which condensers serve to smooth out the sharp breaks when sending impulses and thereby prevent 75 impulses sent over one of the physical circuits being heard on the phantom circuit.

The toll lines 305—306 and 405—406 and the phantom circuit superimposed thereon are similarly equipped to prevent interference. 80

Throughout the drawings I have shown a plurality of batteries but it is to be understood that there is preferably but one battery for each exchange, each battery having 85 its positive terminal grounded. Each exchange also is provided with a busy signaling machine, such as T' , T^2 , etc., an interrupter, such as I' , I^2 , etc.; and with a ringing current generator, such as $Gen.^7$, $Gen.^8$, 90 etc.

Having given a general description of the apparatus I will now proceed to a more detailed description of the operation of the same. Inasmuch as a great deal of the automatic apparatus shown herein is well known and has been described in the publications previously referred to, the operation of such apparatus will be described in a more or less general manner, the details being given 100 only where they have reference in some respect to the application of the principles of my invention. I will first describe how a connection is established between substation A in the No. 1 exchange and substation A^2 105 in the No. 3 exchange, this being the complete connection shown in the drawings and previously referred to. The call is assumed to have originated with the subscriber at substation A and the complete connection is, 110 therefore, handled by the operator at the No. 1 exchange. Afterward certain other connections will be briefly described with a view to demonstrating the great flexibility of the system. 115

Referring now to Fig. 1, the subscriber at substation A , in initiating a long distance call, must first get in communication with a so called recording operator at the No. 1 exchange. Any approved method of accomplishing this object will serve, but since the substation A is an automatic substation, it will be assumed that the subscriber has called the operator automatically as follows: Upon removing the receiver at substation A , the 120 line switch C is operated to extend the line conductors 11 and 12 through to a selector switch, which may be the selector to which the trunk conductors 34, 35, and 36 extend. After the line switch has operated, the sub- 125 130

scriber may manipulate the finger hole dial of his instrument, thereby operating the selector switch to select a group of trunks extending to recording operators' positions; 5 after which the selector operates automatically to connect with an idle one of these trunks, all in a well known manner. The calling subscriber, upon hearing the operator respond, will give her the necessary information, such as the name and address of the person with whom conversation is desired, and also his own name and telephone number; and will then replace his receiver, thereby restoring the line switch and selector 10 switch to normal position. The recording operator in the meantime has written out the data received from the subscriber on a ticket, which is passed to a toll operator whose duty it is to complete the required connection. 15 In the case under consideration the wanted subscriber is located in the No. 3 exchange which must be reached via the No. 2 exchange. The toll operator, therefore, after first testing the toll line 105—106 with the 20 tip of her plug in the regular manner to determine its idle or busy condition, inserts the calling plug of cord circuit P' in the jack J⁵ of toll line 105—106, it being assumed that this toll line was not in use. By the insertion 25 of the plug in the jack a circuit is completed as follows: ground at G² (Fig. 3), winding of relay 74, conductor 73, contact springs 63 and 64 of relay 60, conductor 94, sleeve of jack J⁵, sleeve of plug inserted 30 therein, and winding of sleeve relay 55 to battery B'. Relay 55 upon energizing prepares a circuit for the supervisory lamp L² and also disconnects the test wire 58 from the tip side of the cord. Relay 74, upon energizing, separates contact springs 88, 89, 35 and 90 and contact springs 91, 92, and 93, thereby disconnecting the conductors 71 and 70 from the drop 75 and from the line relays 61 and 62 of the repeater E². Relay 74 40 also prepares a circuit for relay 77 by closing contact springs 86 and 87.

The operator may now throw the key K³ associated with the toll line 105—106, thereby completing an initial energizing circuit 45 for relay 77 as follows: ground at G², contact springs 86 and 87, contact springs 85 and 94, and winding of relay 77 to battery B. The actuation of key K³ also inserts the calling device S³ in a circuit which will be 50 mentioned later. Relay 77, upon energizing, short circuits the contact springs 85 and 94 of the key K³ by means of contact springs 604 and 605; and shifts contact spring 602 from its normal resting place against contact 55 spring 601 to its working position against contact spring 603, thereby completing a circuit including the impulsing relays 76 (F², Fig. 3) and 112 (M², Fig. 4) as follows: ground at G³ (Fig. 4), contact springs 159 60 and 160, contact springs 165, 166, and 167,

winding of relay 112, winding of retardation coil 511, windings 107 and 108 of repeating coil R⁴ in parallel, line conductors 105 and 106 in parallel, windings 103 and 104 in parallel, winding of retardation coil 510, 70 winding of relay 76, contact springs 602 and 603, contact springs 78 and 80, impulse springs 81 and 82 of calling device S³, and resistance 95 to battery B. Relay 76, upon attracting its armature 84, short circuits the 75 condenser 96 through resistance 97, which operation is without particular effect at this time, however, the repeater E² having been disconnected.

At the repeater M², the relay 112, upon 80 attracting its armature 127, completes a circuit for relay 113 as follows: ground at G⁴, resistance 129, contact 128, armature 127, and winding of relay 113 to battery B⁴. Relay 113, upon energizing, separates contact springs 137 and 138 whose function will be described later, and also by its other pair of contact springs completes a circuit for slow acting relay 117 as follows: ground at G⁵, contact springs 159 and 160, contact 85 springs 165 and 166, contact springs 158 and 157, contact springs 140 and 139, and winding of relay 117 to battery B⁴.

In view of the large number of relays which operate almost simultaneously it is 90 thought best to continue with the energizing circuits of these relays before going into particulars concerning their functions separately. Relay 117, upon energizing, completes a circuit for relay 121 as follows: 100 ground at G⁵, contact springs 142 and 143, and winding of relay 121 to battery B⁴. Relay 121, upon energizing, completes the following circuit for relay 123: ground at G⁶, contact springs 150 and 151, and winding of 105 relay 123 to battery B⁴. Relay 123, upon energizing, disconnects the normal ground connection of relay 124, closes its two upper pairs of contact springs (of no consequence at this time), and completes a circuit for 110 cut-off relay 125 (Fig. 5) as follows: ground at G⁶, winding of relay 125, contact springs 175 and 176, and resistance 186 to battery B⁴. The cut-off relay 125, upon energizing, disconnects the line drop 126 in the usual manner. A branch of the last described circuit extends to the sleeve of jack J⁶ where by raising the potential of the sleeve above the normal ground potential the line is made 115 busy to operators in the No. 2 exchange. 120

Returning now to relay 121, this relay, in addition to closing the circuit of relay 123, also opens by its contact springs 152 and 153 a circuit for the upper winding of relay 118 now closed by contact springs of 125 relay 123; and by its contact springs 148 and 149 prepares a circuit for relay 114 which will be described later. The contact spring 151 of relay 121, now connected to ground at G⁶, is seen to have several branch circuits 130.

leading away from it, one of these circuits, that extending to relay 123, already having been mentioned. A second branch circuit extends by way of conductor 204 to the toll 5 selector N⁴ (Fig. 5^a) and will be again referred to. A third branch circuit may be traced by way of contact springs 177 and 178 of relay 124, and by way of conductor 217^a to multiple test contacts in the banks of the 10 toll selectors N', N², etc., (Fig. 5^a), where, by a ground potential on these test contacts, the toll line represented by repeater M² is 15 made busy.

Returning now to the relay 117, this relay, in addition to closing the circuit of relay 121, removes at the same time ground from 20 spring 141 and the conductor attached thereto. This is done to prevent possible interference by an operator at the No. 2 exchange. 25 Should an operator disregard her busy test, plug into jack J⁶ and operate key K⁴ she would operate relay 122, relay 124 being energized over the sleeve of her cord as will be described later, and thereby release the connection. 30 Such an occurrence is prevented by the removal of ground from spring 141. Spring 143, from which a circuit already mentioned extends to relay 121, has also a branch circuit which may be traced by way of contact springs 130 and 131, conductor 203, and contact springs of relay 259 of the selector N⁴ (Fig. 5^a) to the wiper 271 of the said selector, whence it will be traced further hereafter. A further result of the 35 energization of relay 117 is the closure of a circuit for the line relay 250 of the toll selector N⁴ (Fig. 5^a) as follows: ground at G¹⁰, winding 251 of relay 250, contact springs 248 and 249, conductor 202, contact 40 springs 146 and 147, winding 110 of repeating coil R⁴, contact springs 133 and 132, winding 109 of repeating coil R⁴, contact springs 145 and 144, conductor 201, contact springs 246 and 247, and winding 252 of 45 relay 250 to battery B⁵. Upon energizing, the line relay 250 completes a circuit from ground at G¹¹ which extends by way of the winding of slow acting relay 255 to battery B⁵. Relay 255, upon attracting its armature, 50 prepares circuits for the vertical and rotary magnets 256 and 257 in the well known manner.

The foregoing operations have all occurred in response to the insertion of the 55 plug in jack J⁶ and the operation of the key K⁴ at the No. 1 exchange. The operator in charge of the call is now ready to operate the finger hole dial of the calling device S³ in accordance with the digit which corresponds to the level in the banks of the toll 60 selectors assigned to toll lines extending to the No. 3 exchange. Since the required toll line is terminated in the second level (see Fig. 5^a) the proper digit to call is the 65 digit 2.

In response to the manipulation of the dial the impulse springs 81 and 82 are separated twice momentarily thereby interrupting the circuit of the impulsing relays 76 and 112 a corresponding number of times. 70 The resulting deenergizations of relay 76 are of no effect, the automatic apparatus at the No. 1 exchange having been disconnected as hereinbefore described. Relay 112, however, at each deenergization breaks the circuit of relay 113 which relay instantly retracts its armature, thereby closing contact springs 137 and 138 and separating contact springs 139 and 140. Relay 117, being slow 75 acting retains its armature attracted in spite of the interruptions of its circuit at contact springs 139 and 140. Now when relay 112 attracts its armature after each deenergization, it not only completes again the circuit of relay 113 but also, before relay 113 has 80 had time to energize again, sends an impulse to relay 114 over the following path: ground at G⁴, resistance 129, contact 128, armature 127, contact springs 137 and 138, contact springs 148 and 149, contact springs 135 and 134, and winding 116 of relay 114 to battery B⁴. Relay 114, in response to each impulse, 85 attracts its armature and thereby separates contact springs 130 and 131, of no consequence at this time, and contact springs 132 and 133, which, it will be remembered, are 90 included in the previously described circuit of the line relay 250 of the toll selector N⁴.

Before continuing with the operation of the toll selector it will be well to consider 100 more in detail the operation of relays 114, 113, and 112 in repeating the impulses. As the armature of relay 114 approaches the end of its stroke it separates contact springs 134 and 135, thereby breaking its own energizing circuit, and also closes at the same time contact springs 136 and 134, thereby short circuiting its winding 115. Induced currents in winding 115 serve to carry the armature a certain amount further in its 110 stroke. The relay 113 pulls up fairly quick so that the relay 114 only receives a short impulse which is lengthened suitably by the effect of winding 115. It is evident that the 115 length of time the contacts 132 and 133 are separated will be independent of the duration of the deenergization of relay 112, in fact, the combination of the relays 113 and 114 forms an impulse correcting device.

Referring now to Fig. 5^a, the line relay 120 250 of selector N⁴, in response to interruptions of its circuit at relay 114 of repeater M², is deenergized a number of times, sending an impulse at each deenergization from ground at G¹¹ to the slow acting relay 258 125 and the vertical magnet 256 in series. The vertical magnet, in response to these impulses, steps up the shaft until the wipers stand opposite the level assigned to the toll lines extending to No. 3 exchange, or the 130

second level. The relay 258, being slow acting retains its armature during the impulses and closes a circuit for the test relay 259, which relay locks itself to ground at G^{12} , off normal contact 263 having closed at the first vertical step, and also prepares at the same time a circuit for the rotary magnet 257. Since conductor 204 is already grounded at relay 121 of the repeater M^2 , it would be possible to omit the ground G^{12} and upper springs of relay 255. But in view of the fact that the rotary magnet 257 gets its operating ground from this conductor, it is considered advisable to ground it directly in the selector at this time. At the end of the series of impulses the relay 258 deenergizes, thereby completing the circuit of the rotary magnet 257, whereupon the wipers of the selector are started rotating in search of an idle toll line terminating in the level to which they have been raised. As is well known, the rotary magnet interrupts its own circuit and also the locking circuit of the test relay 259 at every energization, the contacts in the latter circuit, however, being short circuited by the test wiper 272 while passing over busy or grounded contacts. As soon, therefore, as the test wiper reaches an ungrounded test contact the test relay 259 deenergizes and opens the circuit of the rotary magnet, whereupon the wipers are brought to rest upon contacts which are terminals of an idle toll line extending to the No. 3 exchange. In the case under consideration, the first set of contacts of the second level is assumed to have been idle; therefore the wipers 270—273, inclusive, are shown resting, respectively, on contacts 274—277, inclusive. During the rotation of the wipers, in case rotation is necessary, the conductor 203, now grounded at relay 117 of the repeater M^2 , is disconnected from the wiper 271 by means of a pair of contact springs of the test relay 259. When the test relay 259 deenergizes, in addition to stopping the rotation of the wipers, this relay completes a circuit which may be traced as a branch of conductor 204 and which extends by way of interrupter contact 264, off normal contact 263, back contact of relay 259, and winding of line switching relay 253 to battery B^5 . The relay 253, upon energizing, disconnects the line conductors 201 and 202 from the windings of the line relay and connects them through to the wipers 270 and 273. The line relay 250 and slow acting relay now deenergize, the circuit of the release magnet 254 being held open by the line switching relay.

As a result of the foregoing operation of the toll selector, the trunk conductors 201, 202, 203, and 204 have been connected, respectively, with trunk conductors 208, 209, 210, and 211, which latter may be traced up-

ward through Fig. 5 and to the right where they terminate in the repeater M^3 (Fig. 6). By means of the associated repeating coil R^7 the line conductors 208 and 209 are inductively connected with the toll line 70 305—306.

It should be remembered at this point that conductors 208 and 204 are both grounded at repeater M^2 (Fig. 4) and that these conductors are continued through to 75 their respective wipers at the toll selector after its operation at practically the same instant, the former by the closure of the upper contacts of relay 259 and the latter by the closure of the interrupter contact 80 264. Bearing these facts in mind the operation of repeater M^3 may be understood without difficulty. The first operation is that of the relay 311 whose energizing circuit may be traced as follows: 85 ground at G^6 (Fig. 4), contact springs 150 and 151, conductor 204, contact 264 (Fig. 5^a), off normal contact 263, wiper 272, bank contact 276, conductor 211, contact springs 361 and 362, and winding of relay 90 311 to battery B^7 . Upon energizing, relay 311 removes the normal ground connection of relay 310 and completes an energizing circuit for cut-off relay 265 (Fig. 5) as follows: ground at G^{14} , winding of relay 95 365, contact springs 326 and 325, and resistance 324 to battery B^7 . The cut-off relay 365, upon attracting its armature, disconnects the drop 366 in the usual manner. A branch of the above circuit extends to the sleeve of 100 jack J^7 where by raising the potential of the sleeve above the normal ground potential the toll line associated with jack J^7 is made busy to operators in the No. 2 exchange.

In addition to the foregoing, relay 311 105 forces its contact springs 331 and 329 into engagement, respectively, with contact springs 332 and 330, thereby completing simultaneously circuits for the upper and lower windings of relay 313. The circuit 110 for the upper winding of relay 313 may be traced as a branch of the energizing circuit of relay 311 as follows: right hand terminal of relay 311, contact springs 349 and 348, contact springs 332 and 331, and winding 115 314 of relay 313 to battery B^7 . The circuit for the lower winding of relay 313 may be traced over the following path: ground at G^5 (Fig. 4), contact springs 142 and 143, contact springs 130 and 131, conductor 203, contact springs of relay 259 (Fig. 5^a), wiper 271, bank contact 275, conductor 210, contact springs 329 and 330 (Fig. 6), contact springs 346 and 347, and winding 315 of relay 313 120 to battery B^7 . Relay 313 is differentially wound and since the energizing circuits of its two windings are completed simultaneously it remains inoperative.

The apparatus is now in the proper condition to enable the operator at the No. 1 ex- 125 130

change to signal the operator at the No. 3 exchange manually, as will be hereinafter described; but since in the present case it is desired to connect automatically with a substation in the No. 3 exchange, certain further operations at the repeater M^3 must be brought about in order to establish an impulsive circuit over the toll line 305—306 for operating the automatic switches in the No. 10 3 exchange.

These further changes at the repeater M^3 are accomplished by the operator at the No. 1 exchange who operates her dial at this juncture in accordance with the digit 1. As 15 a result of the consequent interruption of its circuit, the impulsive relay 112 of repeater M^2 is deenergized momentarily and sends an impulse to relay 114. Relay 114, upon energizing, operates to separate momentarily the 20 contact springs 130 and 131, thereby interrupting current flow in winding 315 of relay 313. The winding 314 at once becomes effective and relay 313 attracts its armature, thereby permanently opening the circuit of 25 winding 315 at contact springs 346 and 347, and substituting therefor the winding of relay 312 by closing contact springs 345 and 346. Before taking up the functions of relay 312, other results of the operation of relay 30 313 may be mentioned briefly as follows: By separating contact springs 343 and 344, a conductor later extended to relay 317 by the operation of relay 318 is opened; by the separation of contact springs 342 and 341, 35 ground is disconnected from contact spring 335 of relay 312; and by the separation of contact springs 339 and 340 an extension of the grounded conductor 311 is disconnected from contact spring 334 of relay 312.

40 Returning now to relay 312, this relay, upon energizing, completes a circuit for the impulsive relays 319 and 414 (Fig. 7) as follows: ground at G^{26} , contact springs 432 and 433, winding of relay 414, winding of 45 retardation coil 413, windings 410 and 411 of repeating coil R^8 in parallel, line conductors 305 and 306 in parallel, windings 370 and 371 of repeating coil R^7 in parallel, winding of retardation coil 320, winding of relay 319, 50 contact springs 337 and 338, contact springs 368 and 367 (Fig. 5), and resistance 369 to battery B^7 . Relay 319, upon energizing, completes an energizing circuit for relay 318 from ground at G^{15} . The operation of relay 55 318, however, is of no importance.

At the No. 3 exchange relay 414, upon attracting its armature 415, short circuits the condenser 412, thereby completing a circuit for the line relays 440 and 441 of the 60 repeater E^8 (Fig. 8) over the following path: ground at G^{17} , winding of relay 440, conductor 436, contact springs 425 and 427, winding 418 of repeating coil R^8 , contact 65 416, armature 415, resistance 417, winding 419 of repeating coil R^8 , contact springs 430

and 428, conductor 435, and winding of relay 441 to battery B^9 . Relay 441, upon energizing, closes a circuit for the slow acting relay 445 as follows: ground at G^{18} , contact springs 448 and 449, and winding of relay 70 445 to battery B^9 . Relay 445 attracts its armature, and by means of contact springs 463, 464, and 465 shifts the normal connection of the sleeve of jack J^8 from the winding of relay 420 (Fig. 7) to battery B^9 by 75 way of resistance 446. In this manner a guarding potential is placed on the sleeve of jack J^8 ; and, furthermore, should an operator disregard her busy test or plug into jack J^8 accidentally she will not release 80 a connection already established automatically, for relay 420 has had its circuit opened as explained. Relay 445 also prepares, by means of contact springs 468 and 469, an energizing circuit for relay 444; and, by 85 means of contact springs 466 and 467, a locking circuit for relay 442.

Relay 440, upon energizing, closes a circuit for the line relay 512 of the connector H^2 (Fig. 9) as follows: ground at G^{21} , winding 90 513 of relay 512, contact springs 536 and 537, conductor 511, contact springs 451 and 450, contact springs 461 and 462, winding of retardation coil 443, contact springs 457 and 456, conductor 510, contact springs 538 and 95 539, and winding 514 of relay 512 to battery B^9 . Line relay 512 energizes over the foregoing circuit and thereby completes an energizing circuit from ground at G^{22} for the slow acting relay 517 which relay in 100 turn prepares a circuit for the vertical magnet 518 in the well known manner. It may be mentioned here that in case selector switches are used the relay 517 will be provided with an extra pair of springs for 105 supplying a holding ground to the selector or selectors.

The operator at the No. 1 exchange may now operate her calling device in accordance with the telephone number of the subscriber 110 at substation A^2 . The digits already called, it will be understood, form no part of the telephone number as listed in the directory; but are special digits which must be prefixed to the regular telephone numbers by 115 operators in distant exchanges who are calling subscribers in the No. 3 exchange via the No. 2 exchange.

The next operation of the calling device 120 results as before in momentary deenergizations of the impulsive relay 112 (Fig. 4), which deenergizations affect relay 114 in a manner hereinbefore described. Relay 114, by means of contact springs 130 and 131, 125 interrupts the circuit of relay 312 (Fig. 6) at each energization; relay 312, in response to these interruptions of its circuit, interrupts the circuit of impulsive relay 414 (Fig. 7); and relay 414, in turn, interrupts the circuit of line relays 440 and 441 of 130

- repeater E³ (Fig. 8). In brief, the interruptions caused by the operation of the calling device are repeated until they finally affect the line relays of the repeater E³.
- 5 At the first deenergization of relay 441, a circuit is completed for slow acting relay 444 as follows: ground at G¹⁸, contact springs 448 and 447, contact springs 469 and 468, and winding of relay 444 to battery B⁹.
- 10 Relays 445 and 444, being slow acting, retain their armatures in operated position during impulses after which relay 444 retracts its armature. In its energized condition relay 444 disconnects the conductors 510 and 511 from conductors 435 and 436, respectively, and from the normally bridged coil 443; substitutes for the latter a direct path by way of contact springs 460 and 461 and contact springs 450 and 451; and completes 20 an initial energizing circuit for relay 442 as follows: ground at G¹⁹, winding of relay 442 and contact springs 458 and 459 to battery B⁹. Relay 442 locks itself in an obvious manner by closing contact springs 25 452 and 453; and also, by separating contact springs 454 and 455, opens the circuit of the line drop 421 (Fig. 7).
- Relay 440, at each deenergization, breaks the circuit of the line relay 512 of the connector H² which responds by sending impulses to the vertical magnet 518 in the well known manner, side switch wiper 526 being in its first position. The vertical magnet thereupon operates to raise the shaft carrying 35 the wipers 530, 531, and 532 until they stand opposite the level of bank contacts in which are located the contacts of the desired line. The slow acting relay 521 is energized in series with the vertical magnet and retains its armature during a series of impulses, thereby closing an energizing circuit for the private magnet 522. At the 40 end of the series of impulses the relay 521 retracts its armature whereupon the private magnet 522 deenergizes and allows the side switch wipers to advance to their second position in the well known manner.
- The operator at the No. 1 exchange may now manipulate her dial in accordance with 45 the final digit of the desired number. The interruptions resulting from the operation of the dial are repeated as before described until they reach the line relay 512 which now, side switch wiper 526 being in its second position, sends impulses to the rotary magnet 519. In response to these impulses the rotary magnet rotates the shaft until the wipers 530, 531, and 532 arrive at the bank contacts 533, 534, and 535, which contacts form one of the multiple terminals of the line of substation A². During the operation of the rotary magnet the relay 521 controls the private magnet as previously described thereby advancing the side switch 50 wipers to their third position.
- By the advance of side switch wipers 527 and 528 to their third position the line conductors 510 and 511 are extended through condensers to the line wipers 530 and 532. By the advance of side switch wiper 525 to its third position the private wiper 531 is connected to ground at G²⁴, thereby completing an energizing circuit from the cut-off winding 544 of the line switch C². By the operation of the cut-off armature 545 the line conductors extending to substation A² are disconnected from their normal connections in the individual line switch C². Bank contact 534 being multiplied to similarly located contacts in the banks of other connectors, 70 the line of substation A² is made inaccessible to other calls in the well known manner. Side switch wiper 526 in its third position completes an energizing circuit for the ringing relay 524 by way of interrupter I². The 75 ringing relay is energized intermittently and operates to project ringing current from the generator Gen.⁵ over the line conductors to the substation A² where the called subscriber is signaled by the ringing of his bell. When 80 the called subscriber removes his receiver in response to the ringing of his bell a circuit is completed in the well known manner for the double wound back bridge relay 515 (ringing relay 524 being temporarily deenergized) 85 which relay, upon energizing, reverses the incoming line conductors 510 and 511 (of no particular consequence) and also completes a circuit for the ring cut-off relay 523. The 90 ring cut-off relay locks itself from ground at G²⁴ and at the same time opens the circuit of the ringing relay 524.
- The operator at the No. 1 exchange, having completed the dialing of the number, 95 may now restore the key K³ to its normal position thereby cutting out her calling device S³ and making it available for use in other connections. The connection with substation A may be at once completed or the operator may wait for the response of 100 the called subscriber at the No. 3 exchange, the method adopted depending ordinarily on whether it is only required to connect with a certain substation at the No. 3 exchange or whether a certain particular person 105 there is wanted. Assuming the latter to be the case, the operator first ascertains that the proper person is at the telephone in the distant exchange; then inserts the other end of her cord circuit P' in the multiple 110 jack J¹³ of the calling subscriber, and operates her ringing key K¹⁰. By the insertion of the plug in jack J¹³, a circuit is completed 115 which may be traced from ground at G²⁵ by way of winding of low resistance sleeve relay 50, sleeve of plug, sleeve of jack J¹³, conductor 15, and cut-off winding 25 of line switch C. The cut-off armature 23 is thereby operated to disconnect line conductors 11 120 and 12 from their normal connections in line 125 130 and 12 from their normal connections in line 130

switch C. A branch of the above circuit extends over conductor 38 to multiple contacts in the banks of connector H' and associated connectors, thereby making the line 5 of substation A busy to incoming calls.

In response to the ringing of his bell the calling subscriber at substation A may now remove his receiver from the hook, when the required connection will have been completed. Current for the transmitter at the calling substation is supplied through the windings of the supervisory relay 51 of the cord circuit P', while current for the transmitter of the called substation A² is supplied through the windings of the double wound back bridge relay 515 of the connector H², all in a well known manner. The complete path for talking currents has been drawn in heavy lines and should be apparent without further explanation.

When the conversation is finished both subscribers will replace their receivers. Upon replacing the receiver at substation A the relay 51 of cord circuit P' is deenergized, thereby lighting the supervisory lamp L'. By this means the operator is informed that the conversation is at an end, whereupon she may remove both plugs of cord circuit P' from the jacks. The removal of the plug 20 from jack J⁵ breaks the circuit of relays 55 and 74. The deenergization of relay 74 breaks the circuit of relay 112 of repeater M² which relay, upon deenergizing breaks the circuit of relay 113. The deenergization 25 of relay 113 is followed by the deenergization of relays 117, 121, 123, and 125 in rapid succession, whereupon the repeater M² is restored to normal condition. Ground having been disconnected from conductors 203 and 30 204 by the deenergization of relays in repeater M, the relay 253 of toll selector N⁴, relays 311, 313, and 312 of repeater M³, and cut-off relay 365 are deenergized. Upon the deenergization of relay 253 the release magnet 35 254 of the toll selector N⁴ is energized whereupon the selector is restored to normal position in the well known manner the circuit of the release magnet being then opened at off normal contact 262. Upon the deenergization of relay 312 the circuit of relays 319 and 414 is broken. Relay 319, upon deenergizing, breaks the circuit of relay 318, whereupon the repeater M³ will have been restored to normal condition. Relay 414, 40 45 upon deenergizing, breaks the circuit of relays 440 and 441 of the repeater E³. The deenergization of relay 441 is followed by the deenergization of relays 445 and 442 in succession. The deenergization of relay 440 45 50 breaks the circuit of the line relay 512 of the connector H², which relay, upon deenergizing, breaks the circuit of relay 517. Relay 517, upon deenergizing, completes a circuit for the release magnet 516, which magnet operates 55 to restore the shaft and side switch wiper to

their normal position, its own circuit being broken thereafter at off normal contact 536. From the foregoing it will be plain that the disconnection and restoration to normal position of all the apparatus is brought 70 about by the removal of the plug from jack J⁵.

If the line of substation A² had been busy when called, the connector H² would have operated after the final series of impulses to 75 connect a lead from the busy signaling machine T² with one side of the calling line, the side switch wipers being held in their second position for this purpose and to prevent connection with the called line. Upon 80 perceiving the busy signal the operator at the distant exchange removes her plug from the jack whereupon the apparatus is restored to normal as hereinbefore described.

I will now describe briefly a few of the 85 many other connections possible with my improved system of long distance calling. Suppose, for example, the operator at the No. 1 exchange wishes to communicate with the operator at the No. 3 exchange. The 90 operator proceeds as in the case of calling a subscriber in the No. 3 exchange up to the point where the toll selector N⁴ has been operated to select the toll line 305-306 extending to the No. 3 exchange. At this 95 point, instead of operating her dial for the digit 1, which operation would have the effect of energizing the differential relay 313 of the repeater M³, the operator at the No. 1 exchange throws her ringing key K¹². 100 The differential relay 313, accordingly, remains inoperative and the automatic apparatus at the No. 3 exchange is not operated. By throwing the key K¹², alternating current is projected over toll line 105-106 by 105 way of repeating coils R³ and R⁴ and thence by way of conductors 201 and 202 to the toll selector N⁴ where the alternating current relay 260 is bridged across these conductors or rather their extensions, conductors 265 110 and 266. Relay 260 vibrates its armature in response to alternating current, and at each energization completes a circuit for the slow acting relay 261 which relay attracts its armature and retains it as long as alternating current continues to flow through the winding of relay 260. Relay 261 is evidently a ringing relay and operates to disconnect the wipers 270 and 273 from conductors 265 and 266 respectively, and to connect them 115 with the terminals of the ringing current generator Gen'. Ringing current is thus projected by way of conductors 208 and 209, repeating coil R⁷, toll line 305-306, and repeating coil R⁸ to the No. 3 exchange where 120 it affects the normally bridged drop 421. The actuation of the drop 421 informs the operator at the No. 3 exchange that she is wanted and she responds by plugging into the jack J⁸. It will be clear that the opera- 130

tors may now converse as required or they may complete connections between subscribers in their respective exchanges.

Again, for example, the operator at the No. 1 exchange may receive a call for a subscriber in the No. 2 exchange. The required connection may be completed substantially as previously described in the case of the automatic connection between the No. 1 and No. 3 exchanges, except that the first digit to be called is 1 instead of 2. The reason for this will be obvious upon inspection of Fig. 5^a; for it is seen in this drawing that the first level of the toll selector N⁴ and associated selectors is the level from which trunks extend to connector switches such as H³, which connectors are adapted to connect with subscribers' lines terminating in the No. 2 exchange. Also, since no second repeater such as M³ is included in the connection, the second special digit 1 may be omitted, it being only necessary after having raised the toll selector to the desired first level, to dial the telephone number of the subscriber in the No. 2 exchange, the connection being completed through the medium of the connector H³ or similar connector in the well known manner.

Inasmuch as the equipment at the No. 3 exchange is exactly like that at the No. 1 exchange it is thought to be unnecessary to describe the process of establishing connections originating at the former, it being understood that such connections are established precisely in the manner already described except that they are in the reverse direction.

At the No. 2 or intermediate exchange, however, the equipment is somewhat different, and it will be briefly described, therefore, how a connection may be established between a subscriber whose line terminates in the No. 2 exchange and a subscriber whose line terminates in the No. 3 exchange, it being assumed that the call originated with the former subscriber. For the purposes of this explanation it will be assumed that the subscriber at substation A' in the No. 2 exchange is to be connected with the subscriber at substation A² in the No. 3 exchange by way of toll line 305—306, repeater E³, and connector H².

The toll operator at the No. 2 exchange, as already mentioned, is provided with cord circuits similar to cord circuit P' (Fig. 2). After ascertaining in the regular manner that the toll line 305—306 is not in use the calling plug of one of these cord circuits is inserted in the jack J⁷ (Fig. 5), thereby completing a circuit in which the cut-off relay 365 and relay 310 of repeater M³ are included in parallel. The former relay is connected to ground at G¹⁴ and the latter relay is connected to ground at G³³, contact springs 328 and 327 now being closed;

and the junction of the two relays is extended to the sleeve of jack J⁷, whence it extends to the exchange battery by way of the sleeve of the plug in connection therewith. The cut-off relay, upon energizing, disconnects the drop 366, while relay 310, upon energizing, prepares an initial energizing circuit for relay 312 by closing contact spring 378 and 379, and also prepares a locking circuit for the same relay by closing contact springs 361 and 377. A branch of the latter circuit extends by way of conductor 211 to multiple test contacts in the banks of toll selectors N', N², etc., thereby connecting ground at G³⁴ to these contacts and making the toll line 305—306 busy to automatic calls.

The operator may now operate the key K⁵ associated with the jack J⁷, thereby inserting the calling device S⁵ in a circuit which will be described hereafter, and at the same time completing a circuit for relay 312 as follows: ground at G³⁴, contact springs 376 and 375, contact springs 378 and 379, contact springs 381 and 380, and winding of relay 312 to battery B⁷. Relay 312, upon attracting its armature, completes an independent energizing circuit for itself as follows: ground at G³⁴, contact springs 377 and 361, contact springs 340 and 339, contact springs 334 and 333, and winding of relay 312 to battery B⁷. Relay 312 also closes in addition to the above locking circuit, a circuit for the impulsing relays 319 (Fig. 5) and 414 (Fig. 7) over a path which has already been traced, except that since key K⁵ is in its operated position, the calling device S⁵ is included in the circuit. Relay 414, upon attracting its armature, closes a circuit for the line relays 440 and 441 of the repeater E³ and these relays in turn energize and perform the functions previously ascribed to them.

The apparatus is now ready for the dialing of the number, which operation proceeds in the regular manner already described, the connection being finally completed, by the insertion of the local end of the cord circuit in the jack J¹⁵ (Fig. 10) of the substation A'. The operator at the No. 2 exchange may also establish automatic connections between local subscribers and subscribers in the No. 1 exchange, the operation being the same as that just described except that a toll line extending to the No. 1 exchange is used together with its associated apparatus.

The foregoing description, it is thought will be sufficient to make the operation of the automatic apparatus in my system clear. It may be mentioned however, that there may be a fourth exchange connecting with the No. 3 exchange in which case the No. 3 exchange will take on the character of an intermediate exchange and will be provided

with equipment like that at the No. 2 exchange. Then an operator in the No. 1 exchange may connect with a subscriber or operator in the No. 4 exchange by way of 5 the No. 2 and No. 3 exchanges, all in an obvious manner.

It has been mentioned heretofore that the toll lines in my improved system are adapted for use in regular manually established 10 connections as well as for automatic connections. It is of course unnecessary to go into any of the details concerning the manual operation, since manual methods of operating toll lines are old and well known 15 in the art. It should be clearly understood, however, that inasmuch as the calling device keys such as K' and K³ (Fig. 3) are not used during such operation, the automatic apparatus will remain inert and inoperative 20 and will not in any way interfere with the regular manual connections.

Brief mention has been made heretofore of the means for preventing interference between two associated toll lines having a 25 phantom circuit superimposed thereon, and for preventing interference between either of two such toll lines and the superimposed phantom circuit. My invention is of course applicable to toll lines which are not phantom; and since the aforesaid method of preventing interference forms no part of my invention, and since it is fully described in the co-pending application of Frank Newforth, hereinbefore mentioned, it is thought 30 to be unnecessary to devote any space to such description in the present application.

It will be seen from the foregoing that I have devised a practical and efficient system of interconnecting a plurality of toll 40 lines and of establishing automatic connections over toll lines so interconnected; and it will furthermore be seen that these results are accomplished without in any way limiting the capacity of such toll lines for 45 individual use according to methods previously available.

While I have described in the foregoing a certain specific embodiment of my invention, I do not wish to be held strictly to the exact 50 form shown herein, for various changes and adaptations will no doubt suggest themselves to persons skilled in the art. I desire therefore to include and have protected by Letters Patent all forms and modifications 55 of my invention which may come within the scope of the appended claims.

What I claim is:

1. In a telephone trunking system, a central exchange, a plurality of branch exchanges, a toll line connecting each branch exchange with the central exchange, a selector switch at the central exchange for each toll line, multiple contacts for each toll line in the bank of each selector switch, 60 multiple jacks at said exchanges for their

connecting toll lines, manual connecting apparatus associated with said jacks for setting up connections between exchanges, and means whereby upon the establishment of a manual connection over any toll line the selector switch associated therewith is disconnected.

2. In a telephone trunking system, a central exchange, a plurality of branch exchanges, a plurality of toll lines connecting each branch exchange with the central exchange, a selector switch at the central exchange for each toll line, multiple contacts for each toll line in the banks of said switches, multiple jacks at said exchanges 75 for their connecting toll lines, manual connecting apparatus associated with said jacks for setting up connections between exchanges, and means whereby upon the establishment of a manual connection over any toll line the selector switch associated therewith is disconnected.

3. In a telephone trunking system, a central exchange, a plurality of branch exchanges, a toll line connecting each branch exchange with the central exchange, a selector switch at the central exchange for each toll line, multiple contacts for each toll line in the banks of each selector switch, local trunk lines in the central exchange also 90 multiplied in the banks of said switches, multiple jacks at said exchanges for their connecting toll lines, manual connecting apparatus associated with said jacks for setting up connections between exchanges, and means whereby upon the establishment of a manual connection over any toll line the selector switch associated therewith is disconnected.

4. In a telephone trunking system, a central exchange, a plurality of branch exchanges, a plurality of toll lines connecting each branch exchange with the central exchange, a selector switch at the central exchange for each toll line, multiple contacts for each toll line in the banks of said selector switches, local trunk lines in the central exchange also multiplied in the banks of said switches, multiple jacks at said exchanges 105 for their connecting toll lines, manual connecting apparatus associated with said jacks for setting up connections between exchanges, and means whereby upon the establishment of a manual connection over any toll line the selector switch associated therewith is disconnected.

5. In a telephone trunking system, a central exchange, a plurality of branch exchanges, a toll line connecting each branch exchange with the central exchange, a selector switch at the central exchange for each toll line, multiple contacts for each toll line in the bank of each selector switch, multiple jacks at said exchanges for their 110 connecting toll lines, manual connecting apparatus associated with said jacks for setting up connections between exchanges, and means whereby upon the establishment of a manual connection over any toll line the selector switch associated therewith is disconnected.

paratus associated with said jacks for setting up connections between exchanges, means at each branch exchange for operating over its connecting toll line the selector switch 5 associated therewith to connect with the toll line extending to any of the other branch exchanges, and means for placing a busy potential upon the sleeve of a multiple jack when the selector switch associated therewith is operated.

6. In a telephone trunking system, a central exchange, a plurality of branch exchanges, a plurality of toll lines connecting each branch exchange with the central exchange, a selector switch at the central exchange for each toll line, multiple contacts for each toll line in the banks of said switches, multiple jacks at said exchanges for their connecting toll lines, manual connecting apparatus associated with said jacks for setting up connections between exchanges, means at each branch exchange for operating over any one of its connecting toll lines the selector switch associated therewith to connect with an idle toll line extending to any of the other branches, and means for placing a busy potential upon the sleeve of a multiple jack when the selector switch associated therewith is operated.

7. In a telephone trunking system, a central exchange, a plurality of branch exchanges, a toll line connecting each branch exchange with the central exchange, a selector switch at the central exchange for each toll line, multiple contacts for each toll line in the bank of each selector switch, local trunk lines in the central exchange also multiplied in the banks of said switches, means at each branch exchange for operating over its connecting toll line the selector switch associated therewith to connect with an idle one of said trunk lines or with the toll line extending to any of the other branch exchanges, and means for placing a busy potential upon the sleeve of a multiple jack when the selector switch associated therewith is operated.

8. In a telephone trunking system, a central exchange, a plurality of branch exchanges, a plurality of toll lines connecting each branch exchange with the central exchange, a selector switch at the central exchange for each toll line, multiple contacts for each toll line in the banks of said selector switches, local trunk lines in the central exchange also multiplied in the banks of said switches, multiple jacks at said exchanges for their connecting toll lines, manual connecting apparatus associated with said jacks for setting up connections between exchanges, means at each branch exchange for operating over any one of its connecting toll lines the selector switch associated therewith to connect with an idle one of said trunk lines or with an idle toll line extending to

any of the other branches, and means for placing a busy potential upon the sleeve of a multiple jack when the selector switch associated therewith is operated.

9. In a telephone trunking system, a central exchange, a plurality of branch exchanges, a plurality of toll lines connecting each branch exchange with the central exchange, a selector switch at the central exchange for each toll line, multiple contacts 75 for each toll line in the banks of said switches, phantom circuits superimposed on certain toll lines of each plurality, means for setting up manual connections over said phantom circuits, and means at each branch exchange for operating over any one of its connecting toll lines the selector switch associated therewith to connect with an idle toll line extending to any of the other branches.

10. In a telephone trunking system, a central exchange, a plurality of branch exchanges, a plurality of toll lines connecting each branch exchange with the central exchange, a selector switch at the central exchange for each toll line, multiple contacts for each toll line in the banks of said selector switches, local trunk lines in the central exchange also multiplied in the banks of said switches, phantom circuits superimposed on certain toll lines of each plurality, means for setting up manual connections over said phantom circuits, and means at each branch exchange for operating over any one of its connecting toll lines the selector switch associated therewith to connect with an idle one of said trunk lines or with an idle toll line extending to any of the other branches.

11. In a telephone trunking system, a first exchange and a second exchange, a first toll line connecting the two, a third exchange, a second toll line connecting the second and third exchanges, subscribers' lines terminating in said first and third exchanges, a jack and an automatic selector switch for each toll line at each exchange, the said switches at the first and third exchanges having access to the subscribers' lines therein and the switches at the second exchange having access to the said toll lines, manually operated means for connecting a calling line in the first exchange with the jack of the toll line extending to the second exchange and for disconnecting the switch 110 at the first exchange associated therewith, means for sending operating impulses over the said first toll line to operate the switch associated therewith at the second exchange 115 to connect with the second toll line, automatic means for disconnecting the switch associated with the said second toll line at the second exchange, automatic means for establishing an operating circuit over the said second toll line for the switch associ- 120 125 130

- ated therewith at the third exchange, automatic means at the second exchange for repeating operating impulses received over the first toll line into the said operating circuit whereby the switch associated with the second toll line at the third exchange may be operated to connect with a called line in the said third exchange.
12. In a telephone trunking system, a first exchange, a second exchange, a toll line connecting the two, a third exchange, a second toll line connecting the second and third exchanges, a selector switch in each exchange for each toll line, subscribers' lines terminating in each exchange, connective circuits in each exchange having access to subscribers' lines terminating therein and themselves accessible to the selector switches therein, multiples of said toll lines accessible to the selector switches in the second exchange, and means for connecting a subscriber's line in the first or third exchange with a subscriber's line in either of the other exchanges, said means including one of said toll lines, a selector switch associated therewith and one of said connective circuits.
13. In a telephone trunking system, a first exchange, a second exchange, a toll line connecting the two, a third exchange, a second toll line connecting the second and third exchanges, a selector switch in each exchange for each toll line, subscribers' lines terminating in each exchange, connective circuits in each exchange having access to subscribers' lines terminating therein and themselves accessible to the selector switches therein, multiples of said toll lines accessible to the selector switches in the second exchange, means for connecting a subscriber's line in the first or third exchange with a subscriber's line in the second exchange, said means including one of said toll lines, a selector switch associated therewith and one of said connective circuits, and means for connecting a subscriber's line in the first exchange with a subscriber's line in the third exchange, said means including one of said toll lines, the selector switch associated therewith, the other of said toll lines and the selector switch associated therewith, and one of said connective circuits.
14. In a telephone trunking system, a central exchange, a second central exchange, a toll line connecting the two, a third central exchange, a selector switch for said toll line at the second exchange, local connective circuits and a toll line to the said third exchange terminating in contacts in the bank of said selector, and means at said first exchange for operating said selector switch over said first toll line to automatically select and connect with an idle connective circuit or an idle toll line to the said third exchange, another switch at the third exchange, and means for controlling said other switch over said first and said second toll lines.
15. In a telephone system, the combination with a toll line entering a central exchange, of a repeater for said toll line at said exchange, a plurality of automatic progressively movable switches, a branch of said toll line extending to one of said switches, a second branch extending to multiple contacts in the banks of said switches, and circuits over said branches controlled by said repeater.
16. In a telephone system, the combination with a toll line entering a central exchange, of a repeater for said toll line at said exchange, a plurality of automatic progressively movable switches, a branch of said toll line extending to one of said switches, a second branch extending to multiple contacts in the banks of said switches, a third branch extending to a jack, and circuits over said branches controlled by said repeater.
17. In a telephone system, the combination with a toll line entering a central exchange, of a repeater for said toll line at said exchange, a plurality of automatic progressively movable switches, a branch of said toll line extending to one of said switches, a second branch extending to multiple contacts in the banks of said switches, means in said repeater controlled over said toll line for closing an operating circuit over said first branch for said selector, and means in said repeater for placing a guarding potential upon test terminals associated with said second branch.
18. In a telephone system, the combination with a toll line entering a central exchange, of a repeater for said toll line at said exchange, a plurality of automatic progressively movable switches, a branch of said toll line extending to one of said switches, a second branch extending to multiple contacts in the banks of said switches, a third branch extending to a jack, means in said repeater controlled over said toll line for closing an operating circuit over said first branch for said selector, and means in said repeater for placing a guarding potential upon test terminals associated with the other branches.
19. In a telephone system, the combination with a toll line entering a central exchange, of a repeater for said toll line at said exchange, a plurality of automatic progressively movable switches, a branch of said toll line extending to one of said switches, a second branch extending to multiple contacts in the banks of said switches, a third branch extending to a jack, means for operating one of said switches to connect with said second branch, and means in said repeater responsive to such connection.

for placing a guarding potential upon the sleeve of said jack.

20. In a telephone system, the combination with a toll line entering a central exchange, of a repeater for said toll line at said exchange, a plurality of automatic progressively movable switches, a branch of said toll line extending to one of said switches, a second branch extending to multiple contacts in the banks of said switches, a third branch extending to a jack, means for operating one of said switches to connect with said second branch, and means in said repeater for completing a circuit for the transmission of impulses over said toll line.

21. In a telephone system, the combination with a toll line entering a central exchange, of a repeater for said toll line at said exchange, a plurality of automatic progressively movable switches, a branch of said toll line extending to one of said switches, a second branch extending to multiple contacts in the banks of said switches, a third branch extending to a jack, means for operating one of said switches to connect with said second branch, and means in said repeater for completing a circuit for the transmission of impulses over said toll line, said last means controlled over said second branch.

22. In a telephone system the combination with a toll line entering a central exchange, of a repeater for said toll line at said exchange, a plurality of automatic progressively movable switches, a branch of said toll line extending to one of said switches, a second branch extending to multiple line and test contacts in the banks of said switches, a third branch extending to a jack, an operator's cord circuit, and means in said repeater responsive to the connection of said cord circuit with said jack for placing a guarding potential upon the said multiple test contacts.

23. In a telephone system, the combination with a toll line entering a central exchange, of a repeater for said toll line at said exchange, a plurality of automatic progressively movable switches, a branch of said toll line extending to one of said switches, a second branch extending to multiple line and test contacts in the banks of said switches, a third branch extending to a jack, an operator's cord circuit, means in said repeater responsive to the connection of said cord circuit with said jack for placing a guarding potential upon the said multiple test contacts, and means associated with said jack for completing a circuit for the transmission of impulses over said toll line.

24. In a telephone system, the combination with a toll line entering a central exchange, of a repeater for said toll line at said exchange, a plurality of automatic progressively movable switches, a normally discon-

nected branch of said toll line extending to one of said switches, a second branch extending to multiple contacts in the banks of said switches, a third branch extending to a jack, means for operating one of said switches to connect with said second branch, means in said repeater responsive to such connection for placing a guarding potential upon the sleeve of said jack and for preventing the closure of said first branch.

25. In a telephone system, the combination with a toll line entering a central exchange, of a repeater for said toll line at said exchange, a plurality of automatic progressively movable switches, a normally disconnected branch of said toll line extending to one of said switches, a second branch extending to multiple line and test contacts in the banks of said switches, a third branch extending to a jack, an operator's cord circuit, and means in said repeater responsive to the connection of said cord circuit with said jack for placing a guarding potential upon the said multiple test contacts and for preventing the closure of said first branch.

26. In a telephone system, a toll line terminating at a central exchange, a repeater in which said toll line terminates, a second toll line terminating at said exchange, a second repeater in which said second toll line terminates, automatic switches, a normally disconnected branch of each toll line extending by way of its associated repeater to one of said automatic switches, a second branch of each toll line extending to multiple contacts in the banks of said switches, means included in said first repeater and controlled over said first toll line for closing the first branch thereof, means for transmitting impulses over said first toll line to operate through the medium of its associated repeater and first branch the switch associated therewith to connect with said second toll line by way of its second branch.

27. In a telephone system, a toll line terminating at a central exchange, a repeater in which said toll line terminates, a second toll line terminating at said exchange, a second repeater in which said second toll line terminates, automatic switches, a normally disconnected branch of each toll line extending by way of its associated repeater to one of said automatic switches, a second branch of each toll line extending to multiple contacts in the banks of said switches, means included in said first repeater and controlled over said first toll line for closing the first branch thereof, means for transmitting impulses over said first toll line to operate through the medium of its associated repeater and first branch the switch associated therewith to connect with said second toll line by way of its second branch, a third automatic switch associated with said second toll line at the distant end, means in

- cluded in said second repeater and controlled from said first toll line via the connected first and second branches for maintaining an operating circuit over said second toll line 5 for said third switch.
28. In a telephone system, a toll line terminating at a central exchange, a repeater in which said toll line terminates, a second toll line terminating at said exchange, a second 10 repeater in which said second toll line terminates, automatic switches, a normally disconnected branch of each toll line extending by way of its associated repeater to one of said automatic switches, a second 15 branch of each toll line extending to multiple contacts in the banks of said switches, means included in said first repeater and controlled over said first toll line for closing the first branch thereof, means for transmitting impulses over said first toll line to operate through the medium of its associated repeater and first branch the switch associated therewith to connect with said second toll line by way of its second branch, 20 a third automatic switch associated with said second toll line at the distant end, means included in said second repeater and controlled from said first toll line via the connected first and second branches for maintaining an operating circuit over said second 25 toll line for said third switch, said last means initially responsive to an impulse transmitted over said first toll line.
29. In a telephone system, a toll line terminating at a central exchange in a repeater, a branch of said toll line, a second line, an automatic switch controlled over said second line and having access to said branch, a second automatic switch associated with 30 said toll line at the distant end, means for transmitting impulses over said second line to operate said first switch to connect with the branch of said toll line, and means in said repeater responsive to an impulse transmitted over said second line for closing an operating circuit over said toll line for said 35 second switch.
30. In a telephone system, a toll line terminating at a central exchange in a repeater, a branch of said toll line, a second line, an automatic switch controlled over said second line and having access to said branch, a second automatic switch associated with said toll line at the distant end, means for transmitting impulses over said second line to operate said first switch to connect with the branch of said toll line, means in said repeater responsive to an impulse transmitted over said second line for closing an operating circuit over said toll line for said 40 second switch, and a circuit for maintaining said last means effective after said impulse is received.
31. In a telephone system, a toll line terminating at a central exchange in a repeater, 45 a branch of said toll line, an automatic switch controlled over said second line and having access to said branch, a second automatic switch associated with said toll line at the distant end, means for transmitting impulses over said second line to operate said first switch to connect with the branch of said toll line, means in said repeater responsive to an impulse transmitted over said second line for closing an operating circuit over said toll line for said second switch, a second line, an automatic switch controlled over said second line and having access to said branch, a second automatic switch associated with said toll line at the distant end, means for transmitting impulses over said second line to operate said first switch to connect with the branch of said toll line, means in said repeater responsive to an impulse transmitted over said second line for closing an operating circuit over said toll line for said second switch, a circuit for maintaining said last means effective after said impulse is received, and additional means in said repeater whereby further impulses transmitted over said second line are repeated over said operating circuit to actuate said second switch.
32. In a telephone system, an automatic switch, a second automatic switch, a repeater, a first line terminating in said first switch, a second line accessible to said first switch and extending by way of said repeater to said second switch, means for transmitting impulses over said first line to operate said first switch to connect with said second line, and means in said repeater responsive to an impulse transmitted over said first line for closing an operating circuit for said second switch.
33. In a telephone system, an automatic switch, a second automatic switch, a repeater, a first line terminating in said first switch, a second line accessible to said first switch and extending by way of said repeater to said second switch, means for transmitting impulses over said first line to operate said first switch to connect with said second line, means in said repeater responsive to an impulse transmitted over said first line for closing an operating circuit for said second switch, a circuit for maintaining said last means effective after said impulse is received, and means in said repeater for repeating further impulses transmitted over said first line into said operating circuit to actuate said second switch.
34. In a telephone system, a line, an automatic switch for said line, a repeater; a second line accessible to said switch and extending to said repeater, a third line extending from said repeater, a second automatic switch associated with said third line, means for transmitting impulses over said first line to operate said first switch to connect with said second line, and means in said repeater initially responsive to another impulse transmitted over said first line for closing and maintaining an operating circuit for said second switch over said third line.
35. In a telephone system, a line, an automatic switch for said line, a repeater; a second line accessible to said switch and extending to said repeater, a third line ex-

tending from said repeater, a second automatic switch associated with said third line, means for transmitting impulses over said first line to operate said first switch to connect with said second line, means in said repeater initially responsive to another impulse transmitted over said first line for closing and maintaining an operating circuit for said second switch over said third line, and means in said repeater for repeating additional impulses transmitted over said first line into said operating circuit to control said second switch.

36. In a telephone system, a line, an automatic switch for said line, a repeater; a second line accessible to said switch and extending to said repeater, a third line extending from said repeater, a second automatic switch associated with said third line, a signal associated with said third line, means for transmitting impulses over said first line to operate said first switch to connect with said second line, means in said repeater initially responsive to another impulse transmitted over said first line for closing and maintaining an operating circuit for said second switch over said third line, means in said repeater for repeating additional impulses transmitted over said first line into said operating circuit to control said second switch, and means then effective for disconnecting said signal.

37. In a telephone system, a line, an automatic switch for said line, a repeater; a second line accessible to said switch and extending to said repeater, a third line extending from said repeater, a second automatic switch associated with said third line, a signal associated with said third line, means for transmitting impulses over said first line to operate said first switch to connect with said second line, a source of signaling current and means controlled over said first line for connecting said source across said second line to operate said signal.

38. In a telephone system, a line, an automatic switch for said line, a repeater; a second line accessible to said switch and extending to said repeater, a third line extending from said repeater, a second automatic switch associated with said third line, a signal associated with said third line, means for transmitting impulses over said first line to operate said first switch to connect with said second line, a source of signaling current, means for connecting said source across said first line, and a relay in said first switch responsive thereto for connecting said source across said second line to operate said signal.

39. In a telephone system, a line, an automatic switch for said line, a repeater; a second line accessible to said switch and extending to said repeater, a third line extending from said repeater, a second automatic switch associated with said third line, a nor-

mally open operating circuit for said second switch superimposed upon said third line, a signal associated with said third line, means for transmitting impulses over said first line to operate said first switch to connect with said second line, a source of signaling current, means controlled over said first line for connecting said source across said second line to operate said signal, and means in said repeater initially responsive to another impulse transmitted over said first line for closing and maintaining said operating circuit.

40. In a telephone system, the combination with a first line and a second line, of a device for repeating impulses from said first line to said second line, said device comprising a relay controlled over said first line, a second relay having two windings for controlling said second line, means controlled by said first relay for sending an impulse to a first winding of said second relay for each impulse received over said first line, said second relay responsive thereto for delivering impulses to said second line, means controlled by said second relay for interrupting the circuit of its first winding and for short circuiting at the same time its second winding, whereby each operation of the said second relay is partly produced by an induced current in its second winding.

41. In a telephone system, the combination with a first line and a second line, of a device for repeating impulses from said first line to said second line, said device comprising a relay controlled over said first line, a second relay having two windings for controlling said second line, means controlled by said first relay for sending an impulse to a first winding of said second relay for each impulse received over said first line, said second relay responsive thereto for delivering impulses to said second line, means controlled by said second relay for interrupting the circuit of its first winding during each impulse, and for short circuiting at the same time its second winding, whereby the duration of each operation of the second relay is made independent of the length of impulses received over said first line.

42. In a telephone system, a line, a source of alternating current, means including an automatic switch and a trunk line terminating therein for extending a connection to said line, ringing equipment in said switch adapted to project ringing current over said line, and means for projecting current from said source over said trunk line to operate said ringing equipment.

43. In a telephone system, a source of alternating current, a line and a signal associated therewith, means including an operator's cord circuit, a trunk line, and an automatic switch in which said trunk line

- terminates for extending a connection to said line, means in said cord circuit for projecting current from said source over said trunk line, and relay equipment in said
- 5 switch responsive to said current for breaking the connection between said trunk line and said line and for projecting ringing current over the said line to operate said signal.
- 10 44. In a telephone system, the combination with first and second line circuits, of an impulse repeater comprising a relay energized over the first line, a second relay for producing interruptions in the circuit of
- 15 the second line, means for producing interruptions in the first line to cause deenergizations of said first relay, and circuit connections whereby at each energization of said first relay following a deenergization a momentary impulse of definite duration is transmitted through said second relay.
- 20 45. In a telephone system, the combination with a first and second line, of an impulse repeater comprising a relay responsive to current impulses received over said first line, a second relay for producing current impulses in said second line, and circuit connections jointly controlled by said relays whereby each time the said first relay
- 25 responds to an impulse the said circuit of the second relay is closed for a definite time independent of the length of the received impulse.
- 30 46. In a telephone system, means for connecting lines automatically comprising a pair of serially related automatic switches, a trunk line extending between said switches and having at one end a fixed terminal in the first of said switches and at the other end a movable terminal in the other of said switches, a branch of said trunk line at each end extending to a manual connective terminal, and a call signal and operators' equipment associated with each branch for connecting lines over said trunk line manually.
- 35 47. In a telephone system, means for connecting lines automatically comprising a pair of serially related automatic switches, a trunk line extending between said switches and having at one end a fixed terminal in the first of said switches and at the other end a movable terminal in the other of said switches, a branch of said trunk line at each end extending to a manual connective terminal, a call signal and operators' equipment associated with each branch for connecting lines over said trunk line manually, and busy test circuits for preventing interference between manual and automatic connections.
- 40 48. In a telephone system, a trunk line, a manual connective terminal and operators' equipment at each end of said trunk line for handling calls thereover manually, incoming and outgoing branches of said trunk line at
- 45 each end which terminate, respectively, in movable and fixed contacts of automatic switches at opposite ends of said trunk line to establish connections over said trunk line automatically in either direction.
- 50 49. In a telephone system, a trunk line, a manual connective terminal and operators' equipment at each end of said trunk line for handling calls thereover manually, incoming and outgoing branches of said trunk line at each end which terminate, respectively, in movable and fixed contacts of automatic switches, means for operating switches at opposite ends of said trunk line to establish connections over said trunk line automatically in either direction, and busy test circuits for preventing interference between manual and automatic connections.
- 55 50. In a telephone system, a central exchange, a plurality of branch exchanges, trunk lines from said branch exchanges to the central exchange, automatic switches associated with each trunk line, a circuit superimposed upon the conductors of each trunk line, each superimposed circuit including the conductor of the trunk line in parallel, multiple contacts of each trunk line in the banks of each of said switches, and means for operating any of said switches over the superimposed circuit of the associated trunk line to connect any two of said trunk lines.
- 60 51. In a telephone system, a central exchange, a plurality of branch exchanges, trunk lines from the branch exchanges to the central exchange, an automatic switch associated with each trunk line, a circuit superimposed upon each trunk line, each superimposed circuit including the conductor of the trunk line in parallel, an operator's position at the central exchange, signals for said operator, means controlled over any of said trunk lines for operating said signal, and means controlled over the superimposed circuit of any trunk line for operating the associated switch to connect two of said trunk lines without operating said signal.
- 65 52. In a telephone system, a calling line, a repeater and an automatic switch for the calling line, trunk lines accessible to said switch, a relay for said repeater responsive to impulses over the calling line to repeat the impulses to said switch to operate the same to connect with any of said trunk lines, a winding of said relay short circuited by the operation of the same for varying the duration of the impulses repeated to said switch.
- 70 53. In a telephone system, a line, an automatic switch for said line, a repeater, a second line accessible to said switch and extending to said repeater, a third line extending from said repeater, a second automatic switch associated with said third line, a normally open operating circuit for said second switch superimposed upon said third line, a

signal associated with said third line, means for transmitting impulses over said first line to operate said first switch to connect with said second line, a source of signaling current, means controlled over said first line for connecting said source across said second line to operate said signal, and means in said repeater initially responsive to another impulse transmitted over said first line for clos-

ing and maintaining said operating circuit, 10 the operating circuit of said second switch so superimposed as to include both sides of the said line in multiple.

Signed by me at Columbus, Franklin county, Ohio, this 14th day of February, 15 1916.

JOHN WICKS.
